US0D1010254S

(12) **United States Design Patent** (10) Patent No.: **US D1,010,254 S**
(45) Date of Patent: ** *Jan. 2, 2024

(54) **DRYER FOR CLOTHING**

(71) Applicant: **LG ELECTRONICS INC.**, Seoul (KR)

(72) Inventors: **Junghwan Lee**, Seoul (KR); **Hoil Jeon**, Seoul (KR); **Sojin Park**, Seoul (KR); **Eunyoung Chee**, Seoul (KR); **Hyewon Kim**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/802,174**

(22) Filed: **Aug. 3, 2021**

(30) **Foreign Application Priority Data**

Feb. 10, 2021 (KR) 30-2021-0007268

(51) LOC (14) Cl. **15-05**

(52) U.S. Cl.

USPC **D32/8**; D32/6

(58) **Field of Classification Search**

USPC D32/1, 5, 6, 8, 10, 25, 28, 35; D7/393; D21/526

(57) **CLAIM**

The ornamental design for a dryer for clothing, as shown and described.

DESCRIPTION

FIG. 1 is a front perspective view of the dryer for clothing showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use of the claimed design.

The broken lines depict portions of the dryer for clothing that form no part of the claimed design.

1 Claim, 8 Drawing Sheets
